MACHINE FOR MAKING BRICKS AND THE LIKE

Filed Jan. 31, 1931

UNITED STATES PATENT OFFICE

SYDNEY H. MARKLE, OF MUSKEGON, MICHIGAN

MACHINE FOR MAKING BRICKS AND THE LIKE

Application filed January 31, 1931. Serial No. 512,555.

The present invention relates to machines for molding bricks and the like; and its object is, generally, to provide such a mold having vertical walls, withdrawing partitions, a member movable over the top of the mold for removing excess material therein, and means for withdrawing the partitions operating in connection with the movement of said member; and more particularly, to provide mechanisms and combinations of parts whereby this general object is accomplished.

These and any other and more specific objects hereinafter appearing are attained by, and the invention finds preferable embodiment in, the structure and mechanism particularly described in the body of this specification and illustrated by the accompanying drawings, in which:

Figure 1 is a top plan view of a machine for making bricks and the like (portions thereof being broken away) and showing bricks formed therein;

Figure 2 is a vertical sectional view thereof taken on line 2—2 of Figure 1;

Figure 3 is a vertical sectional view of a portion of the same taken on line 3—3 of Figure 2;

Figure 4 is a vertical sectional view of the same taken on line 2—2 of Figure 1 but showing the parts in another position;

Figure 5 is a vertical sectional view thereof taken on the same line 2—2 but showing the parts in still another position;

Figure 6 is a top plan view of a horizontal plate seen in Figures 1, 2, 4 and 5;

Figure 7 is a sectional view thereof taken on line 7—7 of Figure 6;

Figure 8 is a side elevational view of one of the blade partitions of the mold; and

Figure 9 is an end view thereof.

The machine for making bricks and the like illustrated by these drawings comprises a suitable base 1 (desirably a metal casting or frame) having a horizontal top bed plate

2, a downwardly extending front end 3 and parallel sides 4, provided with horizontal ways 5 having top and bottom flanges 6, 7. A mold is formed in this base comprising vertical walls 8, 9, 10, 11, a removable bottom 12 and partitions 13 for forming a plurality of separate bricks in the mold simultaneously.

The machine comprises also a hollow upper member 14 having vertical walls 8¹, 9¹, 10¹, 11¹ corresponding with the vertical walls respectively of the mold, and a top hopper portion 15 for filling the mold through this hollow member. The said member 14 is movable horizontally toward and from the front of the base 1, the rolls 16 journaled at 17 on side brackets 18 carried by said member travelling between the flanges 6, 7 of the ways 5. The partitions 13 of the mold are blades cross sectionally thin horizontally and wide vertically, and elongated in the machine's forward-rearward direction (i. e. parallelly with the ways 5) and slidably bear in openings 19, 20 in the mold's front and rear vertical walls 8, 9, the lower edges 21 of these blade partitions bearing on the mold's bottom (the flat 70 plate 12) which is removably supported on lugs or shelves 22 of the base's vertical portions 3 and 23.

The hollow member 14 may be moved forwardly-rearwardly in the ways 5 by hand or through connections with suitable power, such for instance as cranks (not shown) and their connecting rods indicated at 24 pivoted at 25 on said hollow member. Suitable means are provided for longitudinally moving the blade partitions 13 by, or in connection with, the forward-rearward movement of the hollow member 14 in a portion of said member's movement. Such means may be of various forms.

Perhaps the simplest means for this purpose are those particularly illustrated by the drawings, and comprise a horizontal plate 26 secured to, and extending rearwardly from,

said hollow member 14, and having slots 27 elongated in the direction of said member's horizontal movement; the blade partitions 13 have at their inner ends lugs 28 extending upwardly through these slots respectively and through corresponding slots 31 in the bed plate 2, slidably bearing therein, and being provided with retaining nuts 29 on their threaded upper ends.

- 10 When the parts are in the position shown in Figures 1, 2 and 3, in which the vertical walls of the mold and of hollow member 14 are in registration, the mold is filled through the hopper portion 15 with the brick-making material 30, which is tamped or pressed by suitable means (not shown) on the mold's bottom and against its side walls and blade partitions. This done, the hollow member 14 is moved rearwardly on the ways 5 in which movement the front vertical wall 8¹ of member 14 acting as a scraper blade scrapes off the material 30 extending above the mold's vertical walls, moving the same beyond the mold's rear wall 9 and onto the bed plate 2.
- 15 When this rearward movement of member 14 has carried it to approximately the position seen in Figure 4, the ends 32 of the slots 27 strike the lugs 28 of the partition blades and (the movement of member 14 continuing) move these partition blades rearwardly and from between the bricks 33 formed between them. This done, the upright posts 34 engage at their upper ends the bottom plate 12 of the mold and raise the same with the bricks thereon to the position shown in Figure 5, whereupon said plate and bricks may be removed from the machine. These posts 34 may be thus raised by any suitable means, as the lever 35 having a link 36 connecting the same with a horizontal cross bar 37 on which the posts are mounted.

The parts may be returned to initial position for another molding operation, by lowering the posts 34, placing a mold bottom plate 12 in the mold, and moving the hollow member 14 forwardly, in which movement the opposite ends 38 of the slots 27 engage the lugs 28 and move the blade partitions forwardly, the material 30 in said member being pushed along the bed plate 2 by the rear vertical wall 9¹ of member 14 and into the mold.

In order to permit the adjustment of the slots 27 in plate 26 parallelly with the ways 5, this plate is provided with transverse slots 39 through which pass threaded posts 40 carried by the rearwardly extending flange 41 of hollow member 14, these posts having clamping nuts 42. Adjustable threaded stops 43 limit the forward movement of the blade partitions.

This machine may be employed for molding bricks and the like of various forms; and in the illustrated construction holes in the bricks are formed by round rods 44 extend-

ing upwardly from their supporting frame 45 below the bottom 12 of the mold, said bottom being provided with openings 46 through which these rods freely pass.

The hollow member 14 forms a "filling member" for the mold when in the position seen in Figures 1 and 2.

In the position of the hollow member 14 shown in Figure 4, its front wall 8¹ has not passed rearwardly beyond the rear wall 9 of the mold at the time the rearward movement of the blade partitions begins. Any disturbance or upwardly forced movement of the material in the mold by such rearward movement of the partitions is prevented or minimized by the horizontal flange 47 of the wall 8¹ of said member overlying the material; and such disturbance may be even more completely prevented by extending the said flange further toward the front of the machine as indicated in dotted lines at 47¹ in Figure 4.

However the length of the slots 27 may be such and the parts so adjusted that the wall 8¹ of hollow member 14 moves rearwardly to or beyond the mold's rear wall 9 at or after the time the rearward movement of the blade partitions begins and with good molding results.

The invention being intended to be pointed out in the claims, is not to be limited to or by details of construction of any particular embodiment thereof illustrated by the drawings or hereinbefore described.

I claim:

1. In a machine of the character described: a mold having a mouth at its top; a partition member in the mold horizontally movable to and from a position withdrawn therefrom; a filling member movable horizontally above the mold; connections operatively intermediate said members for moving one of them with the movement of the other.

2. In a machine of the character described: a mold having a mouth at its top; a partition member in the mold horizontally movable to and from a position withdrawn therefrom; a hollow filling member horizontally movable above the mold from and to mold-filling position; connections operatively intermediate said members for moving one of them with the movement of the other.

3. In a machine of the character described: a mold having a mouth at its top and side walls one of which has an opening therethrough; a partition member in the mold horizontally movable in said opening to and from a position withdrawn from the mold; a hollow filling member horizontally movable above the mold from and to mold-filling position and having a side wall adapted to remove by the filling member's movement from mold-filling position excess molding material extending above the mouth of the mold; connections operatively intermediate said

members for moving one of them with the other.

4. In a machine of the character described: a mold having a mouth at its top; a partition member in the mold horizontally movable to and from a position withdrawn therefrom; a hollow filling member horizontally movable above the mold to mold-filling position and reversely to a second position adjacent one side of the mold and to a farther third position remote from said side of the mold; connections operatively intermediate said members for moving the partition member to withdrawn position with the movement of the filling member from its second to its third position.

5. In a machine of the character described: a mold having a mouth at its top; a partition member in the mold horizontally movable to and from a position withdrawn therefrom; a hollow filling member horizontally movable above the mold to mold-filling position and reversely to a second position adjacent one side of the mold and to a farther third position remote from said side of the mold; connections operatively intermediate said members for moving the partition member to withdrawn position with the movement of the filling member from its second to its third position, the filling member having a horizontal flange extending over the mouth of the mold in said member's movement toward its second position.

6. In a machine of the character described: a mold having a mouth at its top; a partition member in the mold horizontally movable to a position withdrawn therefrom; a scraper member horizontally movable across said mouth and adapted to remove by its movement in one direction across said mouth excess molding material extending above said mouth, and having a farther movement in said direction; connections operatively intermediate said members for withdrawing the partition member from the mold with the said farther movement of the scraper member.

7. In a machine of the character described: a mold having a mouth at its top; a partition member in the mold horizontally movable to and from a position withdrawn therefrom; a scraper member horizontally movable across said mouth and adapted to scrape by its movement in one direction across said mouth excess molding material extending above said mouth, and having a farther movement in said direction; connections extending directly between said members for withdrawing the partition member from the mold by said farther movement of the scraper member.

8. In a machine of the character described: a mold having a mouth at its top; a partition member in the mold horizontally movable to and from a position withdrawn therefrom; a scraper member horizontally movable across said mouth and adapted to scrape excess mold-

ing material extending above said mouth and having an extension with a slot elongated in the direction of its movement, the partition member having an extension movable in the slot and engaged by the ends thereof to move the partition member by the movement of the scraper member in a portion of the movement of the scraper member.

In testimony whereof I have hereunto set my hand at Grand Rapids, Michigan, this 28th day of January, 1931.

SYDNEY H. MARKLE.
